UNITED STATES PATENT OFFICE

ISAAC A. BAUM, OF CHICAGO, ILLINOIS

CORNER CONNECTION FOR METAL FRAMES

Application filed August 5, 1929. Serial No. 383,523.

My invention relates to building construction and more particularly to corner connections for metal opening construction.

In the use of metal framing for openings in which two vertical and horizontal members are utilized, considerable difficulty has been experienced in constructing a suitable corner connection for the vertical and horizontal members.

10 An object of my invention is to provide a simple and economical securing means for two intersecting metal frame members which is simply manufactured and readily installed on the job by unskilled labor.

15 A further object of my invention is to provide a suitable corner connection for intersecting metal frames of a simple construction yet insuring absolute rigidity and avoiding the possibility of the frames thereafter warping or separating by reason of internal stresses or blows directed thereagainst.

20 A further object of my invention is to provide a metal frame construction having a corner connection which absolutely insures freedom from movement either vertically horizontally or laterally.

25 My invention will be more readily understood by reference to the accompanying drawings in which

30 Fig. 1 is a plan view of a corner connection constructed in accordance with my invention;

Fig. 2 is a rear elevation thereof;

Fig. 3 is a side elevation thereof; and

Fig. 4 is a vertical sectional view on line

35 4—4 of Fig. 1.

By reference to the drawings it will be seen that I have illustrated two intersecting metal opening frames A and B having the rebent plaster defining terminals 10, 11, 12, 40 and 13, the plaster terminals 10 and 11 being suitably welded to the horizontal frame metal B and the plaster terminals 12 and 13 being suitably welded to the vertical members A. The webs of the respective frame members 45 are suitably bent to provide the door stops 14 and 15.

Between the flanges of the vertical frame member A I have welded the channel shaped member 16, having apertures therein adapted 50 to receive bolts 17 and 18 passing there-

through and the web of the member B is provided near its outer extremity with suitable registering apertures for the reception of the bolts 17 and 18 having cooperating nuts 19, 20.

55 On the vertical frames, adjacent to the door stop 15, I provide the tongues 21, 22 which project upward from the web and are adapted to be inserted through registering slots in the web of the horizontal member B.

60 It will be noted that I have constructed the vertical frame members in such a way that a substantial portion is cut out of the metal constituting the door stop 15 at the upper extremity thereof for the reception of 65 the door stop 14 of the horizontal frame member.

66 In installation the vertical members are temporarily set up and the horizontal member B fitted over the vertical member A, so 70 that the tongues 21 and 22 will project through the apertures in the horizontal member. The tongues are then readily bent down into contact with the web of the frame, and a preliminary setting is effected. The bolts 75 17 and 18 are then inserted from the back side of the vertical members, through the registering apertures in the member 15 and the web B and the nuts 19 and 20 are screwed down from the inside of the horizontal channel shaped member B to effect a positive and 80 final rigid connection at the corners.

85 It is obvious that I have herein disclosed a metal frame opening having a corner connection of the utmost simplicity and insuring the absence of any movement laterally by reason of the tongues 21 and 22 firmly engaging the web of the cross member B; the bolts 17, 18 prevent upward movement of the cross member B, and the cut out portion 90 of the vertical door stop prevents any horizontal movement of the cross member. The vertical and cross members are thus rigidly and permanently secured and all possibility of any movement in any direction is thus 95 eliminated.

100 While I have shown and claimed a construction in which the head frame overlies the ends of the said frames, it will be understood that this construction may be reversed

without invention. That is, the same interlocking connection may be made where the side frames overlie the ends of the head frame.

Obviously numerous variations and modifications may be made in the construction herein disclosed and I do not wish to be limited except as indicated in the appended claims.

10 I claim:

1. A corner connection for intersecting vertical and horizontal frame members, comprising a pair of vertically disposed channel shaped metal frame members and a horizontally disposed channel shaped member, said horizontal member having a plurality of spaced slots in the web thereof near the outer extremities of said member, a pair of upwardly extending tongues on each of said 15 vertically disposed members, said tongues being adapted to enter said slots and to be bent over, and threaded means cooperating between said intersecting members near the outer extremities thereof to rigidly secure 20 the same.

2. In combination a pair of vertically disposed frame members, rebent plaster defining strips on said frame members extending longitudinally thereof, a horizontally disposed channel shaped head piece, said head piece having a plurality of spaced slots in the web thereof near the outer extremities, a pair of rebent plaster defining members secured to the flanges of said head member and 30 extending substantially the length thereof, a pair of upwardly extending tongues formed from the metal in the web of said vertical members, said tongues being adapted to be received in the slots in said horizontal member, and threaded means cooperating between 35 said horizontal and vertical members, to firmly join the same together.

3. Means for securing intersecting metal frame members, comprising in combination, 45 vertical and horizontal channel shaped frame members, said horizontal member having a slot near each extremity thereof, an upwardly extending tongue formed out of the metal of the web of said vertically disposed members, said tongues being adapted to be received within the slots in said horizontal member, an apertured metal strip secured to the flanges of each of said vertically disposed members near the upper extremity thereof, and threaded means cooperating between said 55 strip and the web of said horizontal member for securely joining the same.

4. Means for securing intersecting metal frame members against lateral and vertical separation, comprising in combination vertical and horizontal metal frame members, said horizontal member having a plurality of adjacent slots near the extremities thereof, a plurality of tongues extending upwardly 60 from the upper extremity of the vertical

frame members and adapted to be inserted into said slots, a door stop formed out of the metal of said vertical and horizontal members, an apertured metal strip secured to one face of said vertically disposed members near the upper extremity thereof, and threaded means cooperating between said strip and said horizontal member for securely joining the same.

5. Means for securing intersecting metal frame members against lateral and vertical separation, comprising in combination vertical and horizontal metal frame members, said horizontal member having a plurality of adjacent slots near the extremities thereof, a plurality of tongues extending upwardly from the upper extremity of the vertical frame members and adapted to be inserted into said slots, a door stop formed out of the metal of said vertical and horizontal members, a portion of said vertically disposed door stops being cut out at the upper extremity thereof and adapted to receive the door stop formed on the horizontal members, an apertured metal strip secured to one face of said vertically disposed members near the upper extremity thereof, and threaded means cooperating between said strip and said horizontal member for securely joining the same.

6. Means for securing intersecting metal frame members against lateral and vertical separation, comprising in combination vertical and horizontal channel shaped frame members, said horizontal member having a plurality of adjacent slots near the extremities thereof, a plurality of upwardly extending tongues on said vertically disposed members, said tongues being adapted to be received within slots in said horizontal member, door stops formed out of the metal of said vertical and horizontal members, the upper extremities of said vertically disposed door stops being cut out to permit the horizontally disposed door stop to be seated therein, an apertured metal strip secured to the flanges of said vertically disposed members near the upper extremity thereof, and threaded means cooperating between said strip and the web of said horizontal member for securely joining the members together.

7. In combination, a frame consisting of side frames and a head frame, the head frame overlying the ends of the side frame a portion of the head frame having an opening, a tongue formed as a continuation of a part of the side frame, said tongue being adapted to enter said opening and be bent over, a transverse bolt-supporting member fixed to the side frame, and a bolt adapted to engage said supporting member and the overlying portion of the head frame.

In testimony whereof I have affixed my signature.

ISAAC A. BAUM.
